UNITED STATES PATENT OFFICE.

MOSES C. SWEZEY, OF WEST HAVEN, CONNECTICUT, ASSIGNOR TO EMMA E. SWEZEY, OF SAME PLACE.

CASH-CARRIER.

SPECIFICATION forming part of Letters Patent No. 629,219, dated July 18, 1899.

Application filed March 17, 1899. Serial No. 709,463. (No model.)

To all whom it may concern:

Be it known that I, MOSES C. SWEZEY, of West Haven, in the county of New Haven and State of Connecticut, have invented a new Improvement in Cash-Carriers; and I do hereby declare the following, when taken in connection with the accompanying drawings and the letters of reference marked thereon, to be a full, clear, and exact description of the same, and which said drawings constitute part of this specification, and represent, in—

Figure 1, a top or plan view of a carrier constructed in accordance with my invention; Fig. 2, a longitudinal sectional view of the same; Fig. 3, a longitudinal sectional view of a two-wheeled carriage; Fig. 4, a broken sectional view illustrating a modified form of the bearing-head.

My invention relates to an improvement in cash-carriers, and particularly to that class which consists of a frame carrying a wheel or wheels by which the frame is supported on a wire, and more especially to that class in which the wires at the terminals gradually increase in thickness or are provided with coils which gradually increase in size and so as to provide a gradual stop for the cars. To regulate the distance which the car shall travel upon the enlarged portion of the wire, a screw-stud has been arranged in the side of the frame and extending inward so as to impinge upon the enlarged portion of the track; but in all cases, and more especially when the enlarged terminals are formed from a coil, the stud wears the track and deranges the coil.

The object of this invention is to provide a car with a bearing-surface slightly below the wheel and between which and the wheel the enlarged portion of the terminals will be rigidly held, so that the movement of the car will be arrested and held against rebounding; and it consists in the construction as will be hereinafter described, and pointed out in the claims.

The car will preferably consist of two sides A B, formed separately and adapted to be riveted together, and may be formed with bearings a b at the center to support a single wheel C, as shown in Figs. 1, 2, and 4, or it may be formed at opposite ends with bearings c for

the support of wheels C', as shown in Fig. 3. In case only one wheel is employed the opposite ends of the frame will be formed with fingers d, forming guides for the wire. The frame will also be formed with a cup-receiving socket D of any approved construction. 55

Between the ends of the frame and on one or both sides of the center I provide elastic bearing-heads E, and which, as shown in Figs. 2 and 3, may be formed integral with the 60 sides of the frame, which are usually cast from malleable iron, which permits casting of these bearings with the frame, it being understood that one bearing is formed in each section, as clearly shown in Fig. 1. Beneath 65 these bearing-heads E the frame is formed with threaded openings to receive set-screws F, by which the heads E are held rigid and by which they may be slightly adjusted. When one wheel is employed, as shown in 70 Figs. 1 and 2, these heads are arranged on opposite sides and the supporting-arms e therefrom extend upward and inward from the base; but when two wheels are employed, as shown in Fig. 3, one head will be arranged adjacent 75 to each wheel and the arms e' extend upward and outward. The object of providing two bearing-heads is that the car may be checked and held at each terminal.

Instead of forming the bearing-heads E, as 80 shown in Figs. 1, 2, and 3, of cast metal they may be formed from a strip G of sheet metal, as shown in Fig. 4, and for economy of space may be secured to the frame on one side of the center by a screw g or otherwise and extend beneath the wheel on to the head of an adjusting-screw H, mounted in the frame adjacent to the wheel. The sheet-metal strip, however, does not have any spring action, as it is held rigidly against movement away 90 from wire K by the adjusting-screw H, as are the heads in the construction previously described. 85

In operation the car moving in the direction of the arrow, Fig. 2, will, as it approaches 95 the terminal, pass on to the enlarged portion J of the wire K, and such enlarged portion coming between one or both of the heads and the wheel will cause it to bind thereon and so check and hold the car, while at the op- 100

posite terminal the heads will coact with the wheel and the enlarged portion of the wire at that terminal in the same manner in checking and holding the car.

5 In order to permit the car to ride to a greater or less extent upon the coiled or enlarged portion, the head or heads will be raised or lowered so as to allow more or less space between the upper face of the head and the lower edge of the wheel.

Having fully described my invention, what I claim as new, and desire to secure by Letters Patent, is—

1. In a cash-carrier, the combination with a frame and the supporting-wheel therefor, of an elastic bearing-head secured to said frame and extending upward adjacent to the wheel, and an adjusting-screw directly beneath said head, whereby it is held in a rigid position, substantially as described.

15 2. In a cash-carrier, the combination with a frame and a centrally-arranged supporting-wheel, of an elastic bearing-head arranged between the wheel and the outer end of the frame and an adjusting-screw mounted in the frame directly below said head, whereby the

head is held in a rigid position, substantially as described.

3. In a cash-carrier, the combination with a frame, of an elastic bearing formed integral therewith and arranged adjacent to the means for supporting said carrier, and an adjusting-screw mounted in the carrier directly below said head, whereby the head is held in a rigid position, substantially as described.

35 4. In a cash-carrier, the combination with a frame, having a centrally-arranged wheel, and provided at each end with a notch, of an elastic bearing-head arranged between the wheel and one end of the frame, and an adjusting-screw mounted in the frame directly below said head, and adapted to hold the said head in a rigid position, substantially as described.

40 In testimony whereof I have signed this specification in the presence of two subscribing witnesses.

MOSES C. SWEZEY.
